CLAIM

The ornamental design for a packaging machine, as shown and described.

DESCRIPTION

1. Packaging machine

Fig. 1.1 is a back, left-side perspective view of a packaging machine showing our new design;

Fig. 1.2 is a front, left-side perspective view thereof;

Fig. 1.3 is a front elevation view thereof;

Fig. 1.4 is a back elevation view thereof;

Fig. 1.5 is a plan view thereof;

Fig. 1.6 is a right-side elevation view thereof; and

Fig. 1.7 is a left-side elevation view thereof.

1 Claim, 7 Drawing Sheets
